UNITED STATES PATENT OFFICE.

CHARLES A. WRIGHT, OF PHILADELPHIA, PENNSYLVANIA.

DESIGN FOR A CARD.

SPECIFICATION forming part of Design No. 13,567, dated January 30, 1863.

Application filed December 1, 1862. Term of patent 7 years.

To all whom it may concern:

Be it known that I, CHARLES A. WRIGHT, a citizen of the United States, and a resident of Philadelphia, Pennsylvania, have invented or produced a new and original Design for a Card, of which the following is a specification.

My design for a card is fully shown in the accompanying drawings, Figure 1 being a face view of the card, and Fig. 2 a section on the line 1 2.

The card has the outline of a leaf with a short stem, and the edge of the card is beveled, as shown in Fig. 2, the beveled edge being preferably gilded.

15 I claim—

1. The within-described design for a card, said card having the outline of a leaf with a short stem, as shown and described.
2. The within-described design for a card, said card having the outline of a leaf with a short stem, and having a beveled edge, as shown and described.

In testimony whereof I have signed my name to this specification in the presence of two subscribing witnesses.

CHAS. A. WRIGHT.
